(57) **CLAIM**

The ornamental design for a foldable pet litter shield, as shown and described.

DESCRIPTION

FIG. 1 is a front perspective view of a foldable pet litter shield folding pet supplies baffle, showing my new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 is a bottom view showing the foldable pet litter shield in an unfolded state; and, FIG. 9 is a rear perspective view of the foldable pet litter shield of FIG. 1. The broken lines in the drawings depict portions of the foldable pet litter shield, that form no part of the claimed design.
